ABRASIVE WHEEL DRESSER

Harold George Renner, Detroit, Mich.

Application April 13, 1942, Serial No. 438,776

8 Claims. (Cl. 125—11)

This invention relates to devices for dressing abrasive wheels and the like to substantially any desired contour, and has for one of its principal objects the provision of a tool that will enable the ready formation of various arcs on the wheel and also of plane surfaces, including inclined planes tangent to a desired arc.

Another object of my invention is the mounting of a dressing tool, such as a cutting diamond, in a bar carried by an oscillatable cradle, with provisions for adjusting the position of the bar to move the diamond to desired distances on opposite sides of the axis of the cradle, whereby either convex or concave arcs may be produced on the abrasive wheel at will.

A further object of my invention is the arrangement of the diamond-carrying bar for independent oscillatory movement upon and relatively to the cradle in any desired angular position of the cradle, with provisions for restraining the diamond to straight line reciprocation during such oscillations of the bar, whereby plane surfaces may be produced on the wheel at various selected angles.

A further object of my invention is the provision of stop mechanisms whereby the extent of the desired arc or the width of a desired plane surface can be accurately determined and maintained.

Other objects and advantages will be apparent to those skilled in the art from the following description, wherein reference is made to the accompanying drawings illustrating a preferred embodiment of my invention and wherein similar reference numerals designate similar parts throughout the several views.

In the drawings:

Fig. 1 is a plan view of my improved abrasive wheel dressing device.

Fig. 2 is a side elevational view thereof with parts broken away.

Fig. 3 is a detail vertical cross section through the upper portion of my improved dresser, taken substantially on the line 3—3 of Fig. 1.

Fig. 4 is a horizontal cross section taken substantially on the line 4—4 of Fig. 2 and looking in the direction of the arrows.

Fig. 5 is a front elevation of my improved dresser.

Fig. 6 is a detail vertical cross section taken substantially on the line 6—6 of Fig. 2.

Fig. 7 is a detail perspective view of the rear extremity of the cradle and the associated cross bar utilized in my improved dresser, and

Figs. 8, 9 and 10 are detail sectional views

illustrating varied cuts and forms made on abrasive wheels with my improved dresser.

Referring now to the drawings, my improved abrasive wheel dresser is shown as mounted on a supporting frame 11 formed of spaced parallel bottom members 11A and upright end portions 11B. This supporting frame is preferably made of steel or cast iron, and may be secured for use upon a magnetic chuck, or may be otherwise mounted on a pedestal, bracket or the like. In the end pieces 11B are formed bearings for trunnions 12 of a cradle, herein shown as formed with a longitudinal lower member 13 connected at its extremities to end pieces 14, preferably polygonal in cross section, to form guides for vertically adjustable L-shaped blocks 15 carrying a longitudinally extending bar 16 in which the dressing tool 17, such as a cutting diamond, is adjustably secured, as by the set screw 18 threaded in the collar 19 at substantially the central portion of the bar 16. The trunnions 12 are normally arranged at substantially the uppermost portion of the cradle and the turning axis of the cradle is accurately located at a desired distance above the lowermost portion of the fixed lower bar 13, so as to enable accurate micrometer measurements between the lowermost portion of the cradle and the working extremity of the dressing tool 17.

As best shown in Fig. 6, I have provided a vertically adjustable set screw 20 at substantially the central portion of the bar 13, and the lower rounded edge of such set screw projects slightly below the lower surface of the bar 13 for engagement with one jaw of the micrometer. I have found that by arranging the rounded edge of the set screw 20 accurately at a known distance, say 3½ inches below the axis of the cradle, ample room for adjustment for practically all uses of a dressing tool is afforded, and enables ready formation of both convex and concave arcs on the abrasive wheels by suitably adjusting the height of the dressing tool 17 above or below the axis of the cradle. Such vertical adjustment of the dressing tool 17 may be secured in the usual manner by sliding it up and down within the collar 19 if desired, after which it is clamped in the desired position by the set screw 18.

I have also provided for radial adjustment of the longitudinal diamond-carrying bar 16 toward and away from the axis of the cradle. To this end the outer end faces of the L-shaped blocks 15 are grooved to snugly fit the adjacent portion of the polygonally shaped end pieces 14 of the cradle, and straps 15A are formed with their inner faces grooved to snugly fit the adjacent

contours of the polygonal end pieces 14, adjusting screws 15B being threaded through the straps into the blocks 15 so as to clamp such jaws in any desired adjusted position upon the end pieces 14 of the cradle.

In practice, the screws 15B are loosened and the blocks 15 with the attached longitudinal diamond-carrying bar 16 are slid toward or away from the axis of the cradle to a desired new position, after which the screws 15B are turned home sufficiently to clamp the blocks 15 in the new position. The polygonal shape of the end pieces and the interfitting grooves in the blocks 15 and straps 15A enable an automatic maintenance of parallel relations between the blocks 15. However, to enable checking of adjusted positions at the opposite ends of the diamond-carrying bar 16, I preferably mark space indications on side faces of the end members 14 of the cradle, substantially as shown at 21 on Fig. 2.

The diamond-carrying bar 16 has an oscillatory movement upon the blocks 15, as will be herein-after pointed out, such movement being independent of the desired radially adjusted position of the blocks 15 as well as of desired angular positions of the cradle.

Means are provided for oscillating the cradle, as for example, the handle 22, fixed at the forward extremity of one of the trunnions 12 of the cradle. The handle 22 carries a set screw 23 for locking the cradle in various angular positions, as for example, that shown in dotted lines in Fig. 5.

The set screw 23 is preferably provided with a knurled head, for ready turning during the positioning of the cradle, as well as with a suitable slot for a screw driver or other instrument to enable firm anchoring of the cradle in the selected position.

The extent of the oscillations of the cradle may be controlled by suitable stops, and I have herein shown a pair of stop screws 24 adapted to be threaded in any one of a series of tapped holes 25 spaced accurately in the face plate 26 carried by one of the end members 11B of the frame. Each screw 24 passes through the arcuate slot of a stop link 27, which links are of a length slightly greater than the distance between the holes 25. By this arrangement any desired distance between the holes 25 may be secured by adjusting the links 27 relatively to their set screws 24, and these screws and links may be moved at will to any of the several spaced holes 25.

I preferably provide a semi-circular scale 28 upon the face plate 26 and provide a sight opening 29 in the handle member 22 so that the relative angular position of the handle member, and accordingly of the cradle, can be determined, and checked, at will.

In the formation of arcs upon the abrasive wheels, the mechanism heretofore described is sufficient. The height of the working edge of the cutting diamond 17 is first adjusted relatively to the axis of the cradle, as for example, a distance of .01 inch above the cradle axis to form a concave arc on a radius of .01, or a distance of .25 inch below the cradle axis to secure a convex arc with a radius of .25. The extent of the arc is controlled by the swing of the cradle during the dressing operation, and such extent of swing may be limited by suitable positioning of the stops 27 upon the face plate 26.

When it is desired to form plane surfaces upon

an abrasive wheel, I preferably utilize the mechanism now to be described:

One of the L-shaped blocks 15, as the forward block, best shown in Figs. 1 and 4, carries an elongated plate 30 which is formed on its under surface with a cam slot 30A in which is pressed a ball 31, as by means of the spring-pressed plate 32, adjustably fixed on the lower surface of the diamond-carrying bar 16, as by the shouldered screw 33 extending through an aperture in the bar 16 and threaded into the plate 32, a spring 34 being arranged to normally press the ball 31 firmly into engagement with the walls of the slot 30A. The opposite end of the bar 16 is forked, as best shown in Fig. 4, with the width of the longitudinal open slot 35 therein being substantially the same as the width of the end post 14 with which it cooperates. To this end, the sides of this end piece 14 may be turned on a known radius, as for example $\frac{3}{8}$ and the width of the slot 35 formed to $\frac{3}{4}$ inch so as to ride on the curved sides of the post 14. A spring pressed plate 36 may be arranged to firmly hold the forked end of the bar 16 against the upper surface of its L-shaped block 15 during the movements of such bar 16 independently of the cradle. As best shown in Figs. 2 and 3, a shouldered screw 37 may extend through an aperture in the plate 36 and through the slot of the forked end of the bar 16 and then be threaded into block 15 below the bar 16, a spring 38 being arranged between the head of the screw and the plate 36.

A handle 39 may be secured to the bar 16 adjacent the plate 30 to enable oscillations of the bar 16 whenever desired, the end of the bar 16 carrying the ball 31 swinging in the path determined by the slot 30A, while the forked opposite end of the bar 16 turns about and moves relatively to its adjacent end post 14 of the cradle. By suitably arranging the curvature of the slot 30A, the path of the working face of the dressing tool 17 may be maintained in a straight line, so that such tool 17 merely reciprocates back and forth during the oscillations of the bar 16. Such curvature of the slot 30A can be determined mathematically, but I prefer an empirical determination thereof, as by reversing the process and enforcing the travel of the cutting tool 17 between straight line sides of a slot while oscillating the bar 16, and marking the path traveled by the ball 31 while the straight line reciprocations of the cutting tool are being made.

In use, the cradle may be swung to any desired angle, and then the diamond-cutting bar 16 oscillated relatively thereto through the medium of the handle 39, whereby variously inclined plane surfaces may be secured at will. The extent of reciprocatory travel of the working face of the diamond 17 may be controlled by arranging stops 40 in the L-shaped block 15 adjacent the plate 30, as best shown in Figs. 1 and 2. Slide stops 40 are preferably arranged to be moved into and out of the path of movement of the bar 16, as, for example, in apertures adjacent opposite sides of the block 15. These stops 40 preferably have their inner faces spaced from the longitudinal axial plane of the cradle a distance substantially equal to one-half of the width of the bar 16. With the diamond 17 centrally mounted in the bar 16, such arrangement of the stops 40 will serve to limit one end of the line of travel of the diamond in alignment with the longitudinal axial plane of the cradle, the side of the bar 16 contacting one of the stops 40

when the diamond reaches such alignment. Accordingly inclined plane surfaces of accurately determined widths can be secured, with the extremities of one or more of the plane surfaces in any desired angular relation to other surfaces on the abrasive wheel, as for example, with the plane surfaces tangent to the extremities of a central arc formed on the abrasive wheel.

In Figs. 9 and 10, variously inclined surfaces 51 are shown in relation to adjacent arcuate surfaces 52 on abrasive wheel 50, while in Figs. 6 and 8, only arcuate surfaces 52 are shown, although in Fig. 8 the surfaces 52 are formed with different radii.

While the drawings herein show my improved dresser mounted with the frame portions 11A in the lowermost position, attention is called to the fact that the rearmost end portion 11B of the frame has its outer face formed as a plane surface so that it can rest upon a magnetic chuck or the like and form the bottom supporting portion of the frame 11 if it is desired to utilize the dresser in such upright position.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A device for dressing abrasive wheels comprising a supporting frame, a cradle pivoted thereon having substantially parallel end pieces, blocks adjustable along said end pieces radially toward and away from the cradle axis, a bar mounted at its ends upon said blocks for swinging movement with the cradle and also for independent swinging movement relatively to the cradle, a dressing tool adjustably mounted in said bar, the combined adjustments of blocks and dressing tool serving to effect accurate positionings of the working edge of the dressing tool at substantial distances on opposite sides of the cradle axis, means for oscillating the cradle, stops adjustably mounted on the frame to limit the extent of oscillation, and means for independently oscillating said bar.

2. A device for dressing abrasive wheels as recited in claim 1 wherein the ends of said bar are maintained in contact with the upper faces of said blocks by resilient pressure means.

3. A device for dressing abrasive wheels as recited in claim 1 wherein means are provided for securing the cradle in various angular positions and said bar is mounted for oscillation independently of and relatively to said cradle, one end of said bar being pivoted upon one of said blocks and the other end of said bar swinging across the other block.

4. A device for dressing abrasive wheels as recited in claim 1 wherein means are provided for securing the cradle in various angular positions and said bar is mounted for oscillation independently of and relatively to said cradle, while the dressing tool carried by the bar is restrained to reciprocation in a straight line, one end of said bar being formed with bifurcations straddling one of said end pieces of the cradle, and the other end of said bar swinging across the block mounted on the other end piece, the swinging end portion of said bar carrying a ball,

and its cooperating block being formed with a cam slot receiving said ball.

5. A device for dressing abrasive wheels comprising a supporting frame, a cradle pivoted thereon having substantially parallel end pieces, blocks adjustable along said end pieces radially toward and away from the cradle axis, a bar mounted at its ends upon said blocks, a dressing tool adjustably mounted in said bar, the combined adjustments of blocks and dressing tool serving to effect accurate positionings of the working edge of the dressing tool at substantial distances on opposite sides of the cradle axis, means for oscillating the cradle, means for securing the cradle in various adjusted positions, said bar being mounted for independent oscillation relatively to said cradle with one of its ends pivoted adjacent one of said blocks and its other end arranged to swing across the other of said blocks, and a handle attached to the swinging end of said bar for oscillating the bar.

6. A device for dressing abrasive wheels comprising a supporting frame, a cradle pivoted thereon having substantially parallel end pieces, blocks adjustable along said end pieces radially toward and away from the cradle axis, a bar mounted at its ends upon said blocks, a dressing tool adjustably mounted in said bar, the combined adjustments of blocks and dressing tool serving to effect accurate positionings of the working edge of the dressing tool at substantial distances on opposite sides of the cradle axis, means for oscillating the cradle, means for securing the cradle in various adjusted positions, said bar being mounted for independent oscillation relatively to said cradle with one of its ends bifurcated and straddling one of said end pieces adjacent one block, and the other end of said bar swinging across the other block, the swinging end portion of said bar carrying a ball and its cooperating block being formed with a slot receiving said ball, resilient means arranged to hold said bar upon said blocks and said ball within the slot, and a handle attached to the bar for oscillating the bar.

7. A device for dressing abrasive wheels comprising a supporting frame, a cradle pivoted thereon having substantially parallel end pieces, blocks adjustable along said end pieces radially toward and away from the cradle axis, a bar mounted at its ends upon said blocks, a dressing tool adjustably mounted in said bar, the combined adjustments of blocks and dressing tool serving to effect accurate positionings of the working edge of the dressing tool at substantial distances on opposite sides of the cradle axis, means for oscillating the cradle, means for securing the cradle in various adjusted positions, said bar being mounted for independent oscillation relatively to said cradle while the dressing tool carried thereby is restrained to reciprocation in a straight line, one end of said bar being formed with an elongated slot the side walls of which engage one of said end pieces above one block, and the other end of said bar swinging across the other block, the swinging end portion of said bar carrying a ball and its cooperating block being formed with a slot receiving said ball, resilient means arranged to hold said bar upon said blocks and said ball within the slot, and a handle attached to the bar for oscillating the bar.

8. A device for dressing abrasive wheels as recited in claim 1 wherein the dressing tool carried by said bar is restrained to reciprocation in a

straight line whenever said bar is being oscillated independently of the cradle, one end portion of said bar being formed with bifurcations straddling one of said end pieces of the cradle, and the other end portion of said bar swinging across the block carried by the other end piece of the cradle, the swinging end portion of said bar and

its cooperating block carrying interacting cam and cam-follower members guiding the path of movement of the swinging portion of said bar so as to restrain the dressing tool to reciprocating travel in a straight line.

HAROLD GEORGE RENNER.
